UNITED STATES PATENT OFFICE.

MARION R. CASEY, OF CLINTON, SOUTH CAROLINA, ASSIGNOR TO CLINTON CAM COMPANY, OF CLINTON, SOUTH CAROLINA, A CORPORATION OF SOUTH CAROLINA.

LOOM-CAM.

1,208,913.

Specification of Letters Patent. Patented Dec. 19, 1916.

Application filed January 28, 1916. Serial No. 74,793.

To all whom it may concern:

Be it known that I, MARION R. CASEY, a citizen of the United States of America, and a resident of Clinton county of Laurens, State of South Carolina, have invented 5 certain new and useful Improvements in Loom-Cams, of which the following is a full and clear specification.

This invention relates to that well known 10 type of cloth weaving loom in which a rotating cam-shaft is employed for alternately operating the picker-staffs which throw the shuttle back and forth, one of these being located at each end of the cam-shaft in 15 such manner as to coöperate with the pick-ball or roller of the pick-arm to actuate the picker-staff.

The object of this invention is to so construct this cam that it not only increases the 20 life of the cam, but also cushions or dissipates the jar resulting from the blow of the picker ball against the cam periphery, thereby contributing materially to smoothness of running of the loom and the consequent reduction 25 in wear of parts of the loom, as more fully hereinafter set forth.

In the drawings, Figure 1 is a side elevation of a cam constructed in accordance with 30 my invention; Fig. 2 is a sectional view on the line 2—2 of Fig. 1; Fig. 3 is a side elevation of a cam shaft of a loom provided with a pair of cams constructed in accordance with my invention, the usual pick arms of the loom being shown in dotted lines.

35 My invention consists in overweighting, that is, laterally enlarging the cam body at a toe or point just to the rear of the cam point *a*, this enlargement being designated in the drawing by the letter *b*. This enlargement 40 extends from a point just back of the toe of the cam for a considerable distance around the periphery, and is preferably disposed on one face of the cam. This enlargement may be cast integral with the cam, as 45 shown, or it may be made in a separate casting and bolted to the face of the cam, as shown in my co-pending application Serial No. 53,613, filed October 1, 1915. The periphery of the enlargement coincides with 50 the periphery of the main part of the cam, thereby increasing the width of the periphery at the point where the enlargement is disposed.

55 As is well known, the pick ball strikes the cam with considerable of a blow at a point back of the toe of the cam. This "ball," be-

ing in the form of a roller, extends entirely across the periphery of the main part of the cam as well as that of the enlargement, so that the enlargement of the cam at this point 60 greatly increases the bearing surface and thus increases the life of the cam. The main advantage, however, in thus weighting or enlarging the cam at this point is that the enlarged body of metal serves to materially 65 cushion or deaden the blow of the picker ball or roll against the cam. This dissipating effect of the blow of the picker ball results in a much safer operation of the loom and consequently prolongs the life of the 70 working parts of the loom as well as increases its efficiency.

I have found by actual practice that the use of my invention in a loom materially increases the efficiency and the life of the gears 75 that operate the cam shaft and also prevents slipping of the driving belt, thus increasing the life of the belt and insuring a maximum product in each day's run.

As is well known these cams are arranged 80 on the shaft in such manner that they operate the picker staffs alternately, that is, the points of greatest diameter of the cams are arranged at diametrically opposite sides of the shaft. When my cams are used, it 85 will be seen that the weighted portions of the cam will thus be disposed at diametrically opposite points so as to thereby tend to balance the running of the shaft. This balancing of the cam shaft will also tend to contribute to the smooth running of the loom. 90

It will be understood, of course, that the enlargement may extend nearer to the toe portion than I have illustrated and, in fact, may extend entirely to the point of the toe 95 member. In cams of this type, the toe *a* is usually made removable for renewal purposes, and in case a removable toe is used with my invention, it will be seen that a part of the weight may be embodied in the toe. 100 It will also be understood that where the weight is made detachable as in my co-pending application hereinbefore referred to, the toe may be cast integral with the removable part or patch, so as to be separable from the 105 cam with the patch or enlargement.

Having thus described my invention, what I claim is:

1. A loom cam of the class set forth, overweighted at a point back of the toe portion 110 of the cam, for the purpose set forth.
2. A loom cam of the type set forth hav-

ing a weight disposed on it at a point just back of the toe portion of the cam, this weight projecting laterally from the cam and having a periphery coincident with the 5 periphery of the body of the cam, so as to thereby increase the bearing surface of the pick ball.

3. A loom cam of the class set forth, over-weighted at a point back of the toe portion 10 of the cam, said weight being cast integral with the cam.

4. A loom cam of the class set forth, over-weighted at a point back of the toe portion of the cam, said weight being cast integral with the cam and having its outer face coincident with the periphery of the cam, so as to thereby provide an extended wearing surface for the pick ball. 15

In testimony whereof I hereunto affix my signature.

MARION R. CASEY.
